[57] CLAIM

The ornamental design for an artificial fishing lure, as shown and described.

DESCRIPTION

FIG. 1 is a plan view of the artificial fishing lure of the present invention shown in its coiled position;

FIG. 2 is an elevation view of the lure of FIG. 1 as viewed from the right in FIG. 1;

FIG. 3 is a side view of the lure of FIG. 1 shown extended in use;

FIG. 4 is a top view of the lure of FIG. 3;

FIG. 5 is a view similar to FIG. 3 with the head of the lure twisted in the opposite direction to its position in FIG. 3;

FIG. 6 is a view similar to FIG. 1 showing the same lure design with a smooth surface configuration;

FIGS. 7-10 are figures similar to FIGS. 1-4 showing another embodiment of the artificial fishing lure of the present invention; and

FIG. 11 is a view similar to FIG. 7 showing the same lure design with a smooth surface configuration.
